PRINTING TELEGRAPH CIRCUIT

Frederick G. Hallden, Bellerose, N. Y., assignor
to Postal Telegraph-Cable Company (New
York), New York, N. Y., a corporation of New
York

Application October 12, 1937, Serial No. 168,534

14 Claims. (Cl. 178—2)

My invention relates in general to printing telegraph circuits wherein common line conductors are used to interconnect a multiplicity of printing telegraph instruments.

Certain known selective systems rely on code combinations for selectively connecting in called stations. Furthermore, in known systems of this type it has heretofore not been feasible for a subscriber to register a call during the period of communication between a control station and another one of the subscriber stations.

In accordance with my invention these difficulties are overcome by providing at a control station a simple selecting system dependent only upon selected signals of a certain time duration thus greatly simplifying the selecting mechanism at the receiver, and in providing further a calling system with a register at the control station for registering subscribers calls and thus assuring connection of the calling subscriber to the control station as soon as the line is free for this purpose.

Furthermore, in accordance with my invention, privacy is assured for the communication of each subscriber, since means is provided at the control station for disconnecting the selecting apparatus as soon as one subscriber station has been selected, so that no accidental connection of other subscribers to the line may occur.

Also, the system in accordance with my invention permits the use of simple selective apparatus which may be operated by alternating current motors, such as synchronous motors of simple design.

If no alternating current supply is available, I provide a simple direct current switching arrangement to accomplish the selection without utilizing a particular code combination to distinguish the separate subscribers called circuit.

An object of my invention is to provide a selecting means under the control of a station, for making operative the printing telegraph instrument at another desired station.

Another object of my invention is to provide a simple inexpensive selecting device, which may be entirely operated by alternating current.

Another object of my invention is to maintain inoperative the printer equipment at all stations except the one selected by a controlling station.

A further object is to provide for recording calls from any station at the controlling station at any time.

Other operating features and objects of my invention will become apparent as the circuit operation is described, in connection with the accompanying drawings, in which

Figs. 1 and 1A together illustrate a circuit including a controlling station and a remote station according to my invention;

Fig. 1B illustrates a modification for use with the selector circuits illustrated to permit simultaneous connection of several selected stations.

Figs. 2 and 2A illustrate a modified circuit arrangement of my invention.

Fig. 3 illustrates another modification of the circuit in accordance with my invention, and

Fig. 4 illustrates still another modification of my invention operable when an alternating current power source is not available.

Fig. 1 and Fig. 1A illustrate the circuit details of the controlling station and a remote station, respectively. The circuits are shown in their idle condition.

At the controlling station a printer (not shown) may have its keyboard contacts and its printer magnets connected into the circuit at jacks 49 and the printer motor may be connected to power receptacle 31. Similarly the keyboard contacts, printer magnets and printer motor may be connected to jacks 61 and power receptacle 62 at the remote station Fig. 1A. Since printers and their associated motor circuits are well known, these circuits are not illustrated.

In the normal idle condition, negative battery extends through winding of drop 55, winding of relay 44, contacts 47 of relay 29 to line 60. At each station line 60 extends through polar relays 63 and 64 and call box 65, and at the last station line 60 is connected to ground. Negative battery also extends through contacts of jack 53, polar relay 43, and milliammeter 58 to line 59. At each station line 59 extends through polar relay 66, and jacks 61. Jacks 61 are normally shunted by contacts 67 of relay 68. Line 59 is also grounded at the last station. Polar relays 43, 63, 64 and 66 will be operated as indicated when connected to negative battery at the controlling station. Their armatures will be moved to the opposite contact in each case when positive battery is connected to the lines 59 and 60 at the controlling station.

Method of selecting a station

The rotary switch with contacts 1 to 10 and rotor 21 shall be turned to the position corresponding to the number assigned to a station. Let us assume as an illustration that rotor 21 has been set to engage contact 5. Plug 52 shall then be inserted in jack 53. The sleeve of plug 52 will complete an obvious circuit causing operation of relays 50 and 51. Contacts 56 of relay 50 cause energizing of the printer motor. Contacts 55

54 of relay 51 connect positive battery through the printer set at jacks 49 to the tip of plug 52, which when inserted in jack 53 extends positive battery to line 59 at the same time removing 5 the negative battery at an inner spring of the jack. Contacts 30 of polar relay 43 and contacts 71 of polar relay 66 at each station will make upon this reversal of line current. Contacts 71 of relay 66 will light busy lamps 78 at each station. 10 These lamps serve as an indication that the circuit is busy. Non-locking key 42 should now be depressed for a moment. Closure of contacts of key 42 completes a circuit for operating synchronous motor 24 through contacts 34 of 15 relay 32. Guard lamp 41 in series with resistance 39 will also light at this time. As synchronous motor 24 rotates, cams 25 and 27, and brush 23, all of which are attached to the motor shaft, will rotate also. Contacts 26 will close, 20 almost immediately. The contacts shunt the contacts of key 42 and insure that the motor will run for one complete revolution of cams 25, 27, and brush 23. As soon as cam 27 has rotated a short distance, its contacts 28 will open the circuit of relay 29, transferring line 60 from negative battery at contacts 47 to positive battery at contacts 46 and through resistor 36. Contact 48, connected to ground through resistor 37, closes with one spring of contact 47 before the two 25 springs of contact 47 separate, thereby maintaining circuit continuity through drop 55 and relay 44. This prevents release of the drop 55 or operation of register 45 due to release of relay 44 as relay 29 operates or releases. 30 As has just been described, line 60 is connected to positive battery upon release of relay 29. This reverse battery polarity on line 60 causes polar relay 63 at each station to close its contacts. It also opens the contacts of polar 35 relay 64 at each station. Closure of contacts of relay 63 completes an obvious circuit to an alternating current source, causing synchronous motor 72 to rotate. Cams 74 and 76 attached to the motor shaft, rotate with it. Contacts 77 of 40 cam 76 close almost immediately and form a shunt around contacts of relay 63 to insure rotation of the cams for one full revolution. Guard lamp 73, in shunt with synchronous motor 72 will also be lighted and serves as a guard against 45 operation of call box 65 during the selecting period. 50 As the motor 24 at the controlling station continues to rotate, brush 23 will pass over commutator segments 11 to 20 inclusive, in succession. As segment 15 is reached, a circuit will be established from ground through relay 32, brush 23, and segment 15, contact 5 and rotor 21 of switch, and through relay 29 and resistor 38 to positive battery. Relays 32 and 29 will operate 55 when brush 23 engages segment 15. Relay 32 will lock up through its contacts 33, contacts 30 of relay 43 and resistor 40. Contacts 34 will open the circuit to start key 42, preventing restarting of motor 24 until after the release of relay 32. Relay 29 will release as brush 23 leaves segment 15. This short operation and release of relay 29, causes transmission of a short impulse of negative battery to line 60. This will cause closure of the contacts of polar relay 64. As cam 74 has 60 been rotating during this period, the indent in its periphery will permit its contacts 75 to be closed at the time when the short negative impulse caused relay 64 to close its contacts. Relay 68 will therefore operate and lock up through its contacts 70, and contacts 71 of relay 66. Con-

tacts 69 of relay 68 extends power to receptacle 62 for operation of the printer motor while contacts 67 open, thereby removing the short circuit from the printer magnets.

Contacts 28 of cam 27 will close again just before the end of this revolution of cam 27, and will reoperate and maintain operated relay 29. Relay 29, as previously described, when operated, connects line 60 to negative battery. Almost immediately after this operation of relay 29, cam 10 15 25 will open its contacts 26 thereby causing motor 24 to stop. Negative battery on line 60 causes relay 63 to hold its contacts open, so that when cam 76 opens its contacts 77, motor 72 will stop.

Inter-communication may now be carried on 15 between the controlling and the selected station. Cam 74 is adjustable on shaft of motor 72 so that it can be positioned so its contacts 75 close only when the short selecting impulse, corresponding to a predetermined station number is 20 transmitted by the control station. As cams 74 at the various stations are positioned to correspond to different station numbers, only one can be selected at a time by the control station.

To terminate a connection, the plug 52 should 25 be removed at the control station. This de-energizes relays 50 and 51 and reconnects negative battery to line 59 causing relay 66 at the station to open its contacts 71 thereby releasing relay 68. Relay 43 will also open its contacts 39 30 releasing relay 32 so that the circuit is restored to its normal idle condition.

To call from a remote station

A conventional call box 65 is provided at each 35 station. The code wheel of the call box is arranged to interrupt the line circuit, an identifying number of times (different for each station). These interruptions will cause relay 44 to release and operate a like number of times and register 45. The magnets only of which are shown, will record the call. The first interruption of line 60 by the call box will release drop 55, closing the drop contacts and lighting calling lamp 57. The procedure for connecting the calling station 45 is identical to that just described except that rotor 21 shall be set to engage the contact corresponding to the calling station.

To connect to several stations for simultaneous inter-communication, a key 79, Fig. 1B may 50 be added. After one station has been selected as previously described, relay 32 would be locked up, disabling start key 42 until plug 52 is removed from jack 53. Removal of plug 52 would however cause disconnection of the remote station which had been selected. Instead of removing plug 52, key 79 should be momentarily depressed. This opens the lock circuit of relay 32, releasing it. Rotor 21 may be set for another station and calling key 42 depressed again. The 55 second station will now be selected. More stations may be selected in the same manner by momentarily depressing key 79 before each selection. Similar key arrangements may be used with the arrangements shown in the other figures, for permitting simultaneous intercommunication.

Figs. 2 and 2A illustrate an alternate arrangement wherein cam 27 is positioned on the motor shaft so that in the normal position its contacts 70 28 are held open. Relay 29 will therefore normally be released. In this idle condition, negative battery will extend through drop 55, relay 44 and contacts of relay 29 to line 60. Positive battery will be connected to line 60 when relay 75

29 operates. At the remote stations, polar relays 64 are so connected that their contacts will be open when negative battery is connected to line 69 and will close when positive battery is connected to this line. The method of selection is essentially the same as for that described in Fig. 1 except as follows: As cam 27 starts to rotate it will close its contacts 28 for a short period thereby operating relay 29 which connects positive battery to line 60. This impulse is only long enough to assure that relays 63 at the stations will close their contacts until contacts 77 on cams 76 close. Contact 28 on cam 27 will then open and release relay 29 restoring negative battery to line 60. When the brush at the control station engages the commutator segment corresponding to that to which the switch rotor has been set, relay 29 will again be operated for a short period. Relay 29, when operated, connects line 60 to positive battery causing contacts of polar relay 64 to close, selecting a desired station in the same manner as disclosed for Fig. 1. Relay 29 is released as the brush disengages the commutator segment so that negative battery is restored to line 60, which is the normal idle condition.

Fig. 3 illustrates another circuit arrangement in which the synchronous motors at the stations are rotated a predetermined distance, remaining in this position until the circuit is released at the control station, when they are returned to their normal idle position.

The call box 65, relay 44, register 45, jack 53, and plug 52 function as described for Fig. 1. The circuits connecting to and controlled by plug 52 have been omitted as they are identical to those shown for Fig. 1.

Selection of a station by the control station is accomplished by inserting plug 52 in jack 53, setting rotor 21 to engage the desired contact, and momentarily depressing key 42. Closure of contacts of key 42 causes operation of relay 84 which will lock up through its contacts 85. Line 60 will be transferred from negative to positive battery at contacts 86. Contacts 87 complete a circuit for synchronous motor 24 which begins to rotate. Cam 25 will close contacts 26 almost immediately and insure one complete revolution of cam 25. Brush 23 will pass over segments 11 to 20 inclusive. The armature of polar relay 83 at the station will make with its front contact when line 60 is connected to positive battery. Closure of this contact completes a circuit for operating the synchronous motor which rotates cam 80. Cam 80 will continue to rotate until the armature of relay 88 disengages its front contact. As described for Fig. 1, when plug 52 is inserted in jack 53, positive battery is connected to line 59 instead of negative battery. Polar relay 89 will respond to this positive battery and its armature will rest against its back contact.

As brush 23 continues to rotate it will engage a segment which is connected to the contact to which rotor 21 had been set. As the brush engages this segment, a short circuit is established across the winding of relay 84 causing this relay to release, and reconnect line 60 to negative battery. Motor 24 will continue to rotate until the normal position is reached with contacts 26 open.

Negative battery on line 60 causes the armature of polar relay 88 to disengage its front contact, thereby stopping the motor and cam 80, and engage its back contact. If the cam 80 has stopped at a position so that the contacts 82 are

closed, then a circuit will have been completed through back contacts of relays 88 and 89 and contacts 82 for operation of relay 83. This relay, as in the other cases removes the short circuit from the printer and also starts the printer motor.

Cam 80 obviously will have as many stop positions as there are contact positions for rotor 21 at the control station, so that by properly locating contacts 82 at each station, a multiplicity of selections may be obtained.

When plug 52 is removed from jack 53 negative battery will be applied to line 59. The armature of relay 89 will disengage its back contact, releasing relay 83, and engage its front contact. This contact completes a circuit through the back contact of relay 88 and contacts 84, causing the synchronous motor to rotate cam 80 until the normal idle position of the cam is reached. The circuit now will be in its normal idle condition.

While only one remote station is illustrated in Fig. 3 it should be understood that other stations may be connected in series on lines 59 and 60 in a similar manner.

Figs. 1, 2 and 3 make use of synchronous motors to provide time discrimination as a basic means of selection. In some locations an alternating current power supply for operation of these synchronous motors is not available and Fig. 4 illustrates a method of obtaining essentially the same results by using a dial and step by step switches for obtaining selection.

Referring to Fig. 4, relay 44, register 45, plug 52, jack 53 and call box 65 function in the same manner as described for the other figures. To select a station, the plug 52 should be inserted in jack 53, thereby connecting positive battery to line 59 as previously described. Polar relay 90 will move its armature against its back contact. A conventional dial with dial contact 91 and off-normal contacts 92 is provided at the control station. The dial contacts 92 transfer line 60 from negative battery through relay 44 to positive battery, immediately upon rotating the dial from its normal position and during the period that the dial contacts 91 are transmitting dial pulses to line 60. Immediately after transmission of the dial pulses, contacts 92 transfer line 60 back to negative battery again.

When positive battery is connected to line 60, polar relay 93 will move its armature against its front contact energizing relay 94 and the stepping magnet 95 of a minor switch. Relay 94 is of the slow release type which remains operated during dial pulses. The minor switch is of a standard type and so constructed that it advances its wiper 97 one position each time stepping magnet 95 operates. Wiper 97 will be advanced in accordance with the impulse transmitted by dial contacts 91. As previously explained off-normal contacts 92 reconnect line 60 to negative battery at the termination of dial pulses from dial contacts 91. Polar relay 93 will rest against its back contact. Shortly thereafter, relay 94 will release and its contacts will complete a path for operation of relay 100, which includes back contacts of polar relays 90 and 93, wiper 97 and minor switch bank contact 99. Relay 100, as in the other cases, removes the shunt from the printer and also starts the printer motor.

The minor switch off-normal contacts 98 will be held open when wiper 97 is in its normal released position as shown. They will close however upon the first step of the minor switch and

will remain closed until the wiper 97 is returned to its normal position.

As in the circuits previously described, to terminate a connection, plug 52 is removed from jack 53 thereby connecting negative battery to line 59. The armature of polar relay 90 will disengage its back contact opening the circuit of and releasing relay 100. The armature of relay 90 will then engage its front contact, energizing the minor switch release magnet 96, which restores wiper 97 to its normal position. The circuit of release magnet 96, is opened as previously explained, by off-normal contacts 98 when wiper 97 is in its normal position.

15 A guard lamp 101 will light at the station as selecting impulses are received over line 60.

With relays 100 connected to different bank contacts at various stations, a means is provided for their individual selection by the control station.

20 Although my invention has been described in particular embodiments with reference to the circuits shown in the drawings, this description is intended to merely disclose examples of the 25 invention and is not to be construed as a definition of the scope thereof. Other modifications and construction may be used within the scope of the appended claims.

I claim:

30 1. A telegraph system comprising a control station, a plurality of other stations, a transmission line system interconnecting said control station and said other stations, telegraph apparatus at said control stations and each of said 35 other stations, telegraph control means at each of said other stations normally maintaining said telegraph apparatus in inoperative condition, selective means at said control station adjustable to select any desired one of said other stations, means at said control station for applying impulses to the line in accordance with the adjustment of said selective means, means at said other stations responsive to said impulses for initiating an operative condition of said telegraph apparatus at the selected station, means at said 40 control station normally disabling said selective means in response to selection of one of said other stations, alternating current means at said control station for operating said selective means, and alternating current means at said other stations for operating said selected telegraph apparatus.

45 2. A printing telegraph system comprising a control station, a plurality of other stations, a line system interconnecting said control station and said other stations, telegraph apparatus at each of said stations, means at said control station for conditioning one of the lines of said line system for communication between said control station and said other stations, means at said control station for transmitting selective impulses to another of said lines of said line system for selectively controlling the telegraph apparatus at said other stations, means at each of said 50 other stations responsive to said transmitted selective impulses for connecting the selected transmitter to said first line for communication, and means for registering a call from any of said other stations at said control station during 55 periods of no communication and during periods of communication between said control station and another station.

70 3. A printing telegraph system according to claim 2, in which said means at said control station for transmitting selective impulses, and

said means at each of said other stations responsive to said impulses are controlled by synchronously operated motors at said respective stations.

4. A printing telegraph system according to 5, claim 2, in which said means at said control station for transmitting said selective impulses comprises a dial, and said means at said other stations responsive to said impulses comprises a step by step switch.

10 5. A telegraph system comprising a control station, a plurality of other stations, a first conductor interconnecting said control station and said other stations in series for communication, a second conductor for interconnecting said control stations and said other stations, transmitting apparatus at each of said stations, means at said control station for conditioning said first conductor for communication, means at said control station for applying selective signal impulses to 15 said second conductor, and means at each of said other stations responsive to said transmitted impulses for selectively connecting the transmitting apparatus corresponding to the transmitted selective impulses to said first conductor for 20 communication with said control station.

25 6. A telegraph system according to claim 5, further comprising a call box at each of said other stations connected to said second conductor, and a call register at said control station 30 responsive to calls transmitted from said call boxes.

35 7. A telegraph system according to claim 5, further comprising means at said control station normally operative upon selection of one of said other transmitting stations for disabling said means for applying selective impulses, and means manually operative to enable application of other selective impulses to said second conductor for connecting other of said other stations to 40 said first conductor for intercommunication.

45 8. In a telegraph system, a control station, a plurality of subscriber stations, a line interconnecting said control station and said subscribers stations in series, a selective signal means at said control station comprising an adjustable contact device having contacts corresponding to each of said subscribers stations, a rotary switch provided with contacts corresponding to the contacts of said adjustable contact device, and a 50 control alternating current motor for operating said rotary switch, means at said control station for initiating operation of said motor, means responsive to positioning of said rotary switch on the contact corresponding with the selected 55 contact of said adjustable contact device for applying an impulse to said line, selective control means at each of said subscribers stations, comprising an alternating current motor, and means driven by said alternating current motor, said driven means being adjusted to correspond with the contact of said adjustable contact device assigned to the subscriber's station, a connecting circuit, means controlled by signals transmitted from said control station for starting said alternating current motor, and means responsive 60 jointly to the impulse applied to said line and said driven device for operating said connecting circuit.

65 9. A telegraph system according to claim 8, in 70 which said driven device, comprises contact control means and means for returning said contact control to initial position immediately after operation of said connecting circuit.

75 10. A telegraph system according to claim 8 in 75

- which said driven device comprises contact control means, means for operating said contact control means from normal position for operating said connecting circuit and means responsive to 5 return of said connecting circuit to initial un-operated condition for restoring said driven means to normal.
11. A telegraph system comprising a control station, a plurality of subscriber stations, a line 10 interconnecting said control station and said subscribers stations in series, a second line interconnecting said control station and said subscriber stations, a selective signal means at said control stations comprising an impulse dial connected to said line, printer motor circuits and 15 printers at each of said subscribers stations, a control circuit at each of said subscribers stations for operating said motor circuits, a step-by-step rotary switch at each subscriber station, a connection different for each subscriber station 20 from a contact of each of said step-by-step switches to said control circuit, means at each of said subscriber stations for receiving impulses applied to said line by said impulse dial, and 25 means responsive to the number of dial impulses received for stepping said switch to close the motor circuit at the selected subscriber station, and to connect the printer at said selected station to said second line for communication.
- 30 12. In a telegraph system, a control station, a plurality of subscriber stations, transmitters at each of said stations, a first conductor line interconnecting said control station and said subscribers stations for communication, means at 5 each of said subscribers stations normally rendering said transmitters inoperative for communication, a second conductor line, means at said control station cooperating with said second conductor line for selectively rendering a selected one of said transmitters operative for communication over said first conductor line. 10
13. In a telegraph system a plurality of stations connected to a transmission line, means at only one of said stations for selectively controlling communication with any of said other stations, a call register means at said one station, 15 and means at each of said other stations for registering a call at said one station at substantially any time. 15
14. In a telegraph system, a plurality of stations, a transmission line for communication extending to all of said stations, a second transmission line connected to all of said stations, means at only one of said stations for transmitting signals over said second conductor for selectively operatively connecting said other stations to said communication line, a call register at said one station cooperating with said second line, and means at each of said other stations for registering a call at said one station over said second line at substantially any time. 20 25

FREDERICK G. HALLDEN.
